UNITED STATES PATENT OFFICE.

ERNEST C. HAYS, OF WACO, TEXAS.

INCUBATOR.

1,101,742.

Specification of Letters Patent. Patented June 30, 1914.

Application filed January 28, 1914. Serial No. 814,987.

To all whom it may concern:

Be it known that I, ERNEST C. HAYS, a citizen of the United States, residing at Waco, in the county of McLennan and State 5 of Texas, have invented certain new and useful Improvements in Incubators, of which the following is a specification.

My invention relates to incubators, and has for its object the provision of an incubator in which a minimum temperature 10 may be constantly maintained and a predetermined temperature in excess of said minimum temperature automatically maintained and controlled.

15 A further object of the invention is to provide mechanism for the stated purpose which may be adjusted from the outside of the incubator and which will be simple in construction and efficient in operation.

20 Other incidental objects of the invention will appear as the description of the same proceeds, and the invention consists in certain novel features which will be hereinafter first fully described and then more particularly pointed out in the claims.

25 In the annexed drawings: Figure 1 is a plan view of an incubator embodying my improvements; Fig. 2 is a vertical sectional view of the same; Fig. 3 is a detail perspective view of the circuit closer; Fig. 4 is a diagrammatic view showing the arrangement of lights which serve as the heating agent and the circuit closer co-acting therewith.

30 The incubator comprises a double walled casing 1 which is supported in an elevated position on legs 2 and is provided in its bottom with openings 3 to admit fresh air to the interior. The space between the inner 35 and outer walls of the casing is filled with asbestos, mineral wool, or other heat insulating material and at the front of the casing is provided a double hinged door 4 which will permit examination of the incubator 40 and contents of the same and will also provide access thereto. Upon the bottom of the incubator is placed an egg tray 5 which may be of the usual or any preferred construction.

45 Upon the inner side of the top of the incubator is provided a number of incandescent electric lamps 6 which may be of any number according to the size of the apparatus. In the present instance, four lamps are shown arranged in two series, each comprising two lamps. The lamps 6, 6 are permanently connected in the circuit including

conductors 7 and 8 leading to and from the source of electric energy and by a conductor 9, as shown, while the lamps 6, 6^a are permanently connected to the conductors 7 and 8, but are connected with each other by conductors 10 and 11 including an automatic circuit closer 12 which serves to interrupt the circuit and automatically extinguish the lamps 6^a, 6^a when the temperature rises 65 above the predetermined degree.

Secured to and depending from the top of the incubator is a bracket, standard or other form of supporting arm 13 having its lower end bent laterally, as shown at 14, 70 and to the extremity of this lateral arm 14 is secured a thermostat 15 from which a rod 16 rises through the top of the incubator. The thermostat consists preferably of superposed receptacles 17 which may be 75 filled with ether, mercury, or other volatile fluid, and the rod 16 may be secured to or rest upon the receptacle. The upper end of the support 13 is bent laterally so as to fit flat against the inner side of the top of the 80 casing and is secured to the said top by screws or similar fastenings 18, as will be readily understood. To the said support, below and near the upper end thereof, is fulcrumed a beam 19 which extends to the 85 opposite sides of the said support and is equipped near one end with an adjustable counter-weight 20 so as to be properly balanced. Upon the opposite end of the beam is secured a cap or block 21 of insulating 90 material for a purpose which will presently appear. The rod 16 is pivotally connected to the beam between the support 13 and the weight 20, so that, as the thermostat expands or contracts, the rod 16 will be moved 95 upwardly or downwardly and, consequently, the beam will be oscillated about its fulcrum. As before stated, the upper end of the rod 16 extends through the top of the casing and the opening through which it 100 passes may be lined with any convenient form of bushing, indicated at 22. Upon the outer side of the top of the casing, adjacent the said bushing or opening, is a bracket or bearing 23 upon which is pivotally secured 105 a lever 24 extending across the said bushing 22 and carrying at its free end a cap 25 which is adapted to fit over and close an opening 26 provided in the top of the casing. Adjacent the bracket or bearing 23, a set-screw 27 is mounted in the lever 24 in position to be engaged by the upper extremity 110

of the rod 16, and it will be readily understood that by adjusting the said set-screw through the lever the period at which the lever will be actuated may be regulated.

5 Secured to the inner side of the top of the casing is a resilient plate 28 which constitutes the movable member of the circuit closer 12 and is so tempered that it tends to move away from the casing top. As shown 10 clearly in Fig. 2, this plate 28 rests upon the block or cap 21 so that, when the beam 19 is moved upwardly by the expansion of the thermostat and the cap 21 thereby swung downwardly, the resilient plate will spring 15 away from the top of the casing and thereby break the circuit. The fixed member of the circuit closer consists of a screw 29 which is mounted in a bushing 30 in the top of the casing and is provided with a head 31 of 20 vulcanite or other insulating material so that it may be readily adjusted without danger to the operator. This screw 29 passes through and intimately engages a plate 32 which is secured to the inner side of the top 25 of the casing and the conductor 10 is secured directly to the said plate, it being understood that the conductor 11 is secured to the end of the plate 28.

It is thought the operation of the apparatus will be readily understood. As long as 30 the temperature of the incubator is below or at the desired temperature the member 28 of the circuit closer will be in contact with the screw 29 and, consequently, the circuit 35 will be closed so that all the lamps will be burning. The cap 25 will also rest upon the top of the casing so that the opening 26 through the same will be closed. Should the temperature of the incubator rise to a point 40 above the predetermined maximum, the expansion of the thermostat due to the high temperature will lift the rod 16 and the beam 19 will follow the movement of the said rod through its pivotal connection 45 therewith so that the cap or block 21 will be lowered and, consequently, the member 28 will spring away from the screw 29 and thereby break the circuit. The lamps 6^a, 6^a will, consequently, be extinguished and the 50 supply of heat thereby diminished. The continued upward movement of the rod 16 will cause its upper extremity to engage the said screw 27 and thereby lift the lever 24 so that the cap 25 will be raised from the opening 55 26 and the excess of heated air may then escape through the said opening, fresh air being admitted through the openings 3 in the bottom of the incubator so that a thorough ventilation of the apparatus will be automatically effected.

It will be readily noted that the screws 27 and 31 are both adjusted from the outside of the apparatus so that it is not necessary to open the incubator and thereby expose the 60 eggs to an excess of cold air in order to ad-

just the mechanism. It will also be noted that these screws may be so adjusted that the lights 6^a, 6^a will be extinguished before the opening 26 is uncovered and a very thorough ventilation of the apparatus without 70 undue cooling of the eggs may be accomplished. As the temperature within the incubator lowers, the thermostat, of course, will be cooled and will contract so that the beam 19 and the lever 24 will return to their 75 initial normal positions and the escape of air from the incubator will be arrested and the lamps 6^a, 6^a again lighted.

The parts of the apparatus are very simple in their construction and are compact in 80 their arrangement so that they occupy the least possible space within the incubator so that it may be applied to incubators of any type without requiring excessive changes 85 therein and without entailing a burdensome expense. The conductors for the lamps may be placed upon either the inside or the outside of the casing top and when the invention is applied to new incubators they may be embedded within the top so that they will 90 be out of the way and will not be liable to accidental breakage. By adjusting the set-screw 27 so that it will bear constantly upon the upper end of the thermostat rod 16, the 95 lever 24 may be set so that a slight space may be left between the cap 25 and the top of the casing and, consequently, ventilation of the apparatus may be provided without diminishing the supply of heat and this adjustment will be found very advantageous in exceeding cold weather.

What I claim is:—

1. In an incubator, the combination with a casing, of a plurality of electric heaters within the casing to heat the same, a circuit closer in circuit with some of the heaters and comprising a fixed member secured within the casing and a movable member co-acting therewith, a bracket secured within the casing, a beam fulcrumed upon said bracket 105 and bearing at one end against the movable member of the circuit closer, and a thermostatic controlling device mounted on said bracket and pivotally attached to said beam.

2. In an incubator, the combination with a casing, of a plurality of electric heaters therein, a circuit closer within the casing in circuit with some of the heaters and comprising a contact point adjustably mounted in the casing and extending therethrough 110 and a resilient plate secured within the casing and normally in contact with said point, a support within the incubator, a beam fulcrumed upon said support and having one end bearing against the resilient plate, and a thermostatic controlling device mounted upon said support and pivotally attached to 115 said beam.

3. In an incubator, the combination of a casing having an air outlet therein, a lever 120

pivotaly mounted upon the casing, a cap carried by the free end of said lever and adapted to close said air outlet, a support within the casing, a plurality of electric heaters within the casing, a circuit closer in circuit with some of said heaters and comprising a fixed member and a resilient member secured within the casing and normally in contact with said fixed member, a beam 10 fulcrumed upon said support and bearing against the said resilient member, and a thermostatic controlling device having a rod pivoted to said beam and extending through the incubator to actuate the said lever.

15 4. In an incubator, the combination of a casing having an air outlet therein, a lever pivotally mounted upon the casing, a cap carried by the free end of said lever and adapted to close said air outlet, a support 20 within the casing, a plurality of electric

heaters within the casing, a circuit closer in circuit with some of said heaters and comprising a fixed member and a resilient member secured within the casing and normally in contact with said fixed member, a beam 25 fulcrumed upon the said support, a thermostatic controlling device having a rod pivoted to said beam and extending through the incubator to actuate the said lever, a cap upon one end of the beam bearing upwardly against the movable member of the circuit closer, and a counter-balance weight upon the opposite end of the beam.

In testimony whereof I affix my signature in presence of two witnesses.
